UNITED STATES PATENT OFFICE.

ANTON KREJCI, OF LEAVENWORTH, KANSAS.

SHELF FOR BEDSTEADS.

957,890.

Specification of Letters Patent. Patented May 17, 1910.

Application filed January 17, 1910. Serial No. 538,417.

To all whom it may concern:

Be it known that I, ANTON KREJCI, a citizen of the United States, residing at Leavenworth, in the county of Leavenworth 5 and State of Kansas, have invented certain new and useful Improvements in Shelves for Bedsteads, of which the following is a specification.

My invention relates to a shelf for bed- 10 steads, and my object is to provide a simple device of this character which is particularly adapted for use in barracks for displaying shoes and accouterments for inspection.

The device is designed for application to 15 ordinary iron bedsteads, and can be quickly attached to or removed from bedsteads without the use of tools, and when removed may be folded for storage or shipment.

In order that the invention may be fully 20 understood, reference will now be made to the accompanying drawing, in which:

Figure 1 represents a perspective view of the device depending from the rails of a bedstead. Fig. 2 shows the device detached 25 from the bedstead rails and folded ready for storage or shipment.

A designates a shelf which consists preferably of sheet-metal reinforced by a surrounding wire F. Said shelf is further re- 30inforced by a longitudinal strap E and a pair of transverse straps C, which latter have upturned eyes c.

B designates a plurality of supporting members, loosely secured at their lower ends 35 to eyes c, so that they may fold upon the shelf as shown in Fig. 2. The upper terminals b of the supporting members B are of inverted L-form to detachably-engage the bedstead rails D.

G designates a pair of hooks loosely-ex- 40 tending through the shelf and provided at their lower threaded ends with nuts I and springs H, which latter are interposed be- 45tween the former and the shelf to reliably hold the upper ends of the hooks in engage- 50ment with the L-shaped ends of members B when the latter are folded upon the shelf.

From the foregoing it will be understood 55 that I have produced a device of simple, durable and inexpensive construction, and one well adapted for the purpose intended, and while I have shown the preferred form of my device, I, of course, reserve the right to make such changes in the construction and arrangement of parts as properly fall 55 within the spirit and scope of the appended claim.

Having thus described my invention, what I claim is:

A hanging shelf for bed-steeds, comprising, in combination, a sheet metal body, spaced transverse brace members, a middle longitudinal brace member adjoining said transverse brace members, upturned ends formed on said transverse brace members, 60 and provided with eyes, rods looped at their lower ends into said eyes, and formed at their upper ends with overturned hooks 65 adapted to engage over the side rails of a bed stead, and resilient means for clamping 70 said rods against the body of the shelf.

In testimony whereof I affix my signature, in the presence of two witnesses.

ANTON KREJCI.
